PAGE 3

FIG. 1 is a front perspective view of a grille showing my new design;

FIG. 2 is a sectional view taken on section 2—2 of FIG. 1 showing a grille bar of the embodiment of FIG. 1 in side elevation;

FIG. 3 is a front perspective view of a modified form thereof;

FIG. 4 is a sectional view taken on section 4—4 of FIG. 3 showing a grille bar of the embodiment of FIG. 3 in side elevation;

FIG. 5 is a front perspective view of a further modified form thereof;

FIG. 6 is a sectional view taken on section 6—6 of FIG. 5 showing a grille bar of the embodiment of FIG. 5 in side elevation;

FIG. 7 is a rear perspective view of the grilles of FIGS. 1, 3, 5, 11, 12, and 13;

FIGS. 8, 9 and 10 are each enlarged, front perspective views of a fragment of the grille bars of FIGS. 1, 3 and 5, respectively, showing the color contrast;

FIGS. 11, 12 and 13 are front elevations of three additional modified forms of my invention showing contrasting color patterns on the front edges of the grille bars; and

FIG. 14 is a sectional view taken on section 14—14 of any one of FIGS. 11, 12 and 13, showing the grille bars of these forms of the invention in side elevation.

The dominant features of my design reside in the portions shown in full lines. The appearance of the grilles and grille bars in perspective view from the diametrically oppo-

site corner of the grille is the same as the perspective views of FIGS. 1, 3, 5, and 7—10. The stippled surfaces on the grille bars in the drawings represent surfaces of a color which contrasts with the color of the non-stippled or plain surfaces.

This application is a continuation-in-part of my co-pending application Serial No. D. 68,579, filed Jan. 30, 1962, now abandoned.

I claim:

The ornamental design for a grille, as shown and described.
